MOVABLE CLAMP FOR METALLIC ROOF COVERINGS

Filed Sept. 6, 1930

Fig. 12

Inventor:

Eugen Wender

UNITED STATES PATENT OFFICE

EUGEN WENDER, OF FRANKFORT-ON-THE-MAIN, GERMANY

MOVABLE CLAMP FOR METALLIC ROOF COVERINGS

Application filed September 6, 1930, Serial No. 480,123, and in Germany August 2, 1929.

The invention concerns a clinger for erect grooves at a flexible metallic roof covering. The novelty consists in the clinger being movable and composed of two parts, one of 5 which is firmly connected to the roof base, while the other part is grooved or by other means joined to the covering, with allowance for displacement along and transverse to the slope of the roof.

10 Figs. 1-12 show examples of different executions of the invention.

Part *a* of the clinger is in the usual way firmly connected to the base of the roof which may consist of any material whatever. The 15 erect standing part *b* is grooved or by other means joined to the covering, which also secures the possibility of displacement in equal directions between covering and base, the allowance for displacement along and vertical 20 to the slope of the roof being secured between parts *a* and *b* of the clinger. Even in the case of strong winds the covering will neither be untied or ripped off the base, nor will it ever suffer from change of temperature, on 25 account of the movable connection between parts *a* and *b* of the clinger, since the covering may expand and contract, wandering so to speak on the base of the roof.

Fig. 1 is a perspective view of a piece of 30 roof with a metallic covering.

Figs. 2 and 3 show a lateral view of the clinger, vertical to the direction of the erect groove and the slope of the roof.

Fig. 4 is a view of the clinger vertical to 35 the direction of the erect groove and the slope of the roof.

Fig. 5 is a lateral view of another execution of the invention exactly as in Figs. 2 and 3.

40 Fig. 6 is another view of Fig. 5 in the same manner as Fig. 4.

Figs. 7 and 8 show still another execution in the same manner as Figs. 2 and 4.

45 Figs. 9 and 10 show the invention anew in another execution similar to Figs. 2 and 4, except that part *a* is shown in Fig. 9 in cross-section and in Fig. 10 in longitudinal-section.

50 Figs. 11 and 12 show still another execution of the clinger the views being also ver-

tical to or in the direction of the slope of the roof.

The invention is also marked with the letter *a* in Fig. 1, with reference to its part *a* fixed to the base of the roof. From Fig. 2 55 results that the clinger composed of the two principal parts *a* and *b* is placed between two ends of the roof covering joining laterally to one another and that part *a* is firmly connected to the roof covering and part *b* to the 60 two ends of the covering forming an erect groove.

Fig. 3 shows the clinger with its part *b* and the two adjacent ends of the roof covering ready grooved. Nevertheless, it is not 65 absolutely essential that part *b* is grooved together with the erect groove of the roof covering, this can also be joined in another way, e. g., by means of soldering to the roof covering.

70 Fig. 4 shows that part *b* can move in the slots *c* of part *a* by the section *x* along the groove and the slope of the roof and that since part *b* is made of thin sheet metal, the flexibility or springing of same secures a 75 transversal movement or swinging in a direction vertical to that of the first movement. The double arrows in Figs. 2 and 3 illustrate this possibility of swinging or moving.

80 Figs. 5 and 6 show a clinger, the erect part *b* of which is joined pivoting to the stationary part *a*, thus effecting for part *b* allowance for longitudinal displacement on joint bolt *d* as well as for lateral swinging. The 85 double arrows of Fig. 5 illustrate the swinging extent of the erect part *b* of the clinger, while Fig. 6 shows the longitudinal displacement by the section *x*.

89 Figs. 7 and 8 show a clinger the parts of which both *a* and *b* are connected like ball joints which likewise secure a freedom of motion in all directions parallel to the surface of the roof.

95 Figs. 9 and 10 show a further design which allows part *b* of the clinger to be tipped up and to be longitudinally displaced by a part *d* which shows the shape of a bolt. Also in this case a displacement by the section *x* (Fig. 100

10) may take place in a direction vertical to the swinging plane of Fig. 9.

5 Figs. 11 and 12 finally show a clinger in a design which secures the freedom of motion or flexibility in two directions running vertically one to the other. Part *b* is connected to part *a* by means of two steerers *e* of thin sheet metal. These steerers *e* allow 10 on the one hand (Fig. 12) a swinging extending over the section *x*, on the other hand, in consequence of their thin material they allow, by means of springing, a deflection in a vertical direction to the former swinging plane (Fig. 11.).

15 I claim as my invention:—

A clinger consisting of two principal parts for erect grooves in a flexible metallic roof covering of which the one principal part is firmly connected to the base of the roof, and 20 the other principal part to the roof covering, characterized by an elastic joint existing between the principal parts which secures freedom of motion between the principal parts and thus also between the base of the roof 25 and the covering of the roof along and vertical to the slope of the roof as described.

Dated this 30th day of April, 1931.

EUGEN WENDER.
